UNITED STATES PATENT OFFICE.

JOSEPH D. KILGORE, OF COLUMBUS, OHIO.

TOY PISTOL.

1,368,402.

Specification of Letters Patent. Patented Feb. 15, 1921.

Application filed July 14, 1919. Serial No. 310,704.

To all whom it may concern:

Be it known that I, JOSEPH D. KILGORE, a citizen of the United States, residing at Columbus, in the county of Franklin and State of Ohio, have invented new and useful Improvements in Toy Pistols, of which the following is a specification.

This invention relates to toy pistols of the type in which paper caps in strip form are fed forward beneath a hammer, and exploded by the operation of a trigger.

The invention has as its object the provision of a pistol which is simple in construction, which may be inexpensively manufactured, and which, due to its marked simplicity of structure, is unusually efficient in operation.

Another object of the invention is to provide a pistol, the working parts of which may be all thoroughly tested prior to the assembly of the pistol.

A still further object of the invention is the provision of a pistol which may be readily loaded, and the ammunition strip initially fed forward by a very simple operation.

The above and other more obvious objects of my invention, which will become apparent as the description proceeds, are attained by a construction which comprises, broadly, a casing of any suitable form to which is pivotally secured a plate adapted to be entirely concealed within the casing and having located thereon the firing and feeding mechanism of the pistol. The feeding and firing mechanism, as well as the ammunition support, are located upon the plate in such a manner that they may function when disassociated with the casing and hence may be thoroughly tested prior to insertion in the casing.

In the accompanying drawings in which there is disclosed one embodiment of my invention,

Figure 1 is a side elevational view of the pistol showing the plate carrying the ammunition and firing and feeding mechanism withdrawn from the casing for the loading of the pistol.

Fig. 2 is a view similar to Fig. 1 showing the manner in which the tape is initially fed forward after the placing of the same upon the supporting pin.

Fig. 3 is an elevational view of the working parts of the pistol removed from the casing showing the same in normal position.

Fig. 4 is a view similar to Fig. 3, showing the position of the parts upon the retraction of the trigger, and just prior to the release of the hammer for the firing.

Fig. 5 is a view showing the position of the parts immediately after the hammer has struck the cap and prior to the release of the trigger by the finger of the operator.

In the drawings, A indicates a casing of any usual or suitable form having a hollow grip or stock *a* adapted to receive a plate B, which may be removably pivoted to the casing at 10 in such a manner that it may be freely swung without the grip for loading or inspection of the working parts. The plate B is normally maintained within the casing by means of a pivoted latch 11, a lip 12 on which is adapted to engage the curved end 13 of a wall 14 formed on the plate B, the wall serving to close the grip portion of the casing when the plate B is swung within the casing.

As will be observed, the plate B carries the entire operating mechanism of the toy, more clearly shown in Figs. 3, 4 and 5. This mechanism comprises a trigger 15 fulcrumed to the plate by means of a stud 16, and having an arm 17 to which is freely pivoted a sear 18 by means of pintles 19 formed upon the sear and extending through aligned openings in the trigger arm. The sear is formed at each end and upon opposite sides with lips 20, 21, the latter lip having connected thereto a contractile spring 22 secured at its other end to an upstanding lug 23 upon the plate B. The sear lip 20, is adapted to engage a shoulder 24, formed upon a laterally extending retracting toe 25 of a hammer 26. The hammer is pivoted upon a stud 27 and is urged to the position shown in Fig. 3 by means of a spring, the central portion of which is wound around the hammer pivot and having one arm 28 abutting the head 29 of the hammer, and the other arm 30 resting upon the upper edge of the wall 14.

From the above description, it should be clear that pivotal movement of the trigger in opposition to the tension of the spring 22, which not only holds the trigger in the position shown in Fig. 4, but also tends to rock the sear 30 about its pintles 19 and cause an engagement of the lip 20 with the shoulder 24, causes a retraction of the hammer 26 in opposition to the spring 28, 29 to the position shown in Fig. 4.

With this same movement of the trigger there is brought about a feeding of the cap tape T which is coiled about a pin 31 upon the lower end of the plate B. As will be observed, the trigger 15 is formed with an arm 32 through an opening in which is passed a pintle 33 upon a Y-shaped feed dog 34. The feed dog is bifurcated or forked, one finger 35 of the same being connected to the trigger in the manner described and the other finger 36 being adapted to engage the tape and press the same against a feed wall 37 upon the plate B, the upper end of this wall serving as a firing abutment or anvil for the hammer head. A depending arm 38 of the feed dog is adapted to slide beneath a guide lip 39, struck out from the plate B, and has secured thereto by any suitable means, such as the rivet 40, a leaf spring 41, which serves to urge the arm 38 of the feed dog against its guide lip 39 during movement of the feed dog by the trigger. It should thus be clear that movement of the trigger from its normal position, shown in Fig. 3, to the position shown in Fig. 4 results not only in a retraction of the hammer, but also in an upward movement of the feed dog, the finger 36 of which pressing the tape T against the feed wall 37 carries the cap portion of the tape beneath the hammer head 29.

With the working parts of the pistol in the position shown in Fig. 4, further movement of the trigger results in the engagement of the arm 32 upon the trigger with the lip 20 of the sear, the latter being disengaged from the shoulder 24, and permits the spring 28 to force the hammer head 29 against the cap upon the tape previously moved into position by the feed dog. Subsequent release of the trigger by the operator permits the spring 22 to return the parts to the position shown in Fig. 3.

It should be noted that the working parts of the feeding and firing mechanism are related in an extremely simple manner, that no dependency is placed upon springs for the feed of the tape, and that the feed mechanism and the trigger are returned to normal position by means of the spring 22. It should further be noted that the firing abutment, the movable parts of the firing mechanism, the feed mechanism and the ammunition are all supported upon the plate B which is pivotally and removably connected to the casing; the parts being located upon the plate in such a manner that they will function when the plate is removed from the casing. This is an important advantage from a manufacturing standpoint as it permits the thorough testing of the operating mechanism prior to the assembling of the plate B with the pistol casing.

The plate B is normally concealed within the grip or stock of the pistol casing but when it becomes necessary to inspect the

mechanism or to load the pistol, the latch 11 is swung downwardly to the position shown in Figs. 1 and 2, and the plate B moved to the position shown in Fig. 1, whereby a new coil of caps may be placed upon the pin 31, and the end of the coil carried up along the feeding wall beneath the arm 36 of the feed dog. In order to obtain the initial feeding of the tape to place the first cap beneath the hammer, pivotal movement of the plate B is made as shown in Fig. 2 so that the end of the trigger engages the barrel of the casing, resulting in an upward movement of the feed dog and the placing of a cap beneath the hammer head. This movement need be carried only until the parts reach the position shown in Figs. 2 and 4, as it is not desirable that the sear lip 20 be disengaged from the hammer to permit the firing of the first cap upon the tape.

It should be understood that I have shown in the accompanying drawings but one form in which my invention may be embodied, and that such variations or modifications may be made therein as come within the scope of the following claims, wherein I define the breadth of my invention.

Having thus described my invention what I claim is:

1. A toy pistol comprising two relatively movable parts, one of said parts having located thereon the ammunition and the feed mechanism, and means on said part co-operating with the feed mechanism adapted to engage a relatively stationary abutment upon movement of said part to actuate the feed mechanism.

2. A toy pistol comprising two pivotally connected parts, one of said parts containing the ammunition and the feeding and firing mechanism, and means positioned to be engaged by the trigger upon relative movement of said two parts whereby the feeding mechanism may be actuated.

3. A toy pistol comprising a casing, a plate movably connected to said casing and adapted to be received in said casing, said plate having located thereon the feeding and firing mechanism of the pistol, said feeding and firing mechanism being unconcealed when said plate is moved without the casing.

4. A toy pistol comprising a casing, a plate movably and detachably connected to said casing and adapted to be received in said casing, said plate having located thereon the feeding and firing mechanism of the pistol, said feeding and firing mechanism being unconcealed when said plate is moved without the casing.

5. A toy pistol comprising a casing, a plate movably secured to said casing having an anvil and firing mechanism located thereon, the anvil and firing mechanism with the exception of the trigger being en-

- tirely concealed within said casing whereby the operator is protected from the flare-back of the explosion and being unconcealed and adapted to function when said plate is 5 without the casing.
6. A toy pistol comprising a casing, a plate pivotally secured to said casing, an anvil, a striker and actuating mechanism on the plate, said striker and the anvil being entirely concealed by the casing and being adapted to be uncovered when said plate is moved without the casing.
7. A toy firearm comprising a casing member, a plate pivotally secured to said 10 casing member and adapted to nest therewith, feeding and firing mechanism located entirely on said plate and being unconcealed when said plate and casing member are not in nested relation, said feeding and 15 firing mechanism being operative when unconcealed and when said plate and casing member are disassociated whereby the mechanism may be tested before assembly of the 20 firearm and concealment of the feeding and firing mechanism.
8. A toy firearm comprising a casing member, a plate pivotally secured to said 25 casing member and adapted to nest therewith, an anvil, and feeding and firing mechanism located entirely on said plate and being unconcealed when said plate and casing member are not in nested relation, said feeding and 30 firing mechanism being operative when unconcealed and when said plate and casing member are disassociated whereby the mechanism may be tested before assembly of the 35 firearm and concealment of the feeding and firing mechanism.
9. A toy firearm comprising a casing member, a plate pivotally secured to said 40 casing member and adapted to nest therewith, an anvil, feeding and firing mechanism and an ammunition support located entirely on said plate and being uncon- 45 sealed when said plate and casing member are not in nested relation, all of said parts being adapted to function when uncon-
- cealed and when said plate and casing member are disassociated whereby the mechanism may be tested before assembly of the 50 firearm and concealment of the feeding and firing mechanism.
10. A toy pistol comprising a casing member having a stock portion, a plate pivotally secured to said casing member and 55 adapted to come to nested relation with the stock portion thereof, an anvil, and feeding and firing mechanism located entirely upon said plate and being unconcealed when said parts are disassociated, said feeding 60 and firing mechanism being concealed when said plate and casing member are moved to nested relation and being adapted to function when unconcealed and when said plate and casing member are disassociated. 65
11. A toy pistol comprising a casing member having a barrel portion and a hollow stock portion, a plate movably secured to said casing member and adapted to be moved into said hollow stock portion, feeding and firing mechanism located entirely upon said plate and adapted to be unconcealed when the plate is moved without said casing, said feeding and firing mechanism being operative when unconcealed. 70 75
12. A toy pistol comprising a casing member having a barrel portion and a hollow stock portion, a plate movably secured to said casing member and adapted to be moved into said hollow stock portion, feeding and firing mechanism located entirely upon said plate and adapted to be unconcealed when the plate is moved without said casing, said feeding and firing mechanism being operative when unconcealed and when 80 85 said plate and casing member are disassociated.

In testimony whereof I have hereunto set my hand in presence of two subscribing witnesses.
